[57] CLAIM

The ornamental design for a container, as shown.

DESCRIPTION

FIG. 1 is an exploded top perspective view of a container showing my new design;

FIG. 2 is a front elevational view thereof, with the handle member removed for clarity of illustration;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is a front elevational view of the container cover, shown separately for clarity of illustration;

FIG. 9 is a right side elevational view thereof;

FIG. 10 is a top plan view thereof;

FIG. 11 is a rear elevational view thereof;

FIG. 12 is a left side elevational view thereof;

FIG. 13 is a bottom plan view thereof;

FIG. 14 is rear elevational view of the container handle shown separately for clarity of illustration;

FIG. 15 is a left side elevational view thereof;

FIG. 16 is a top plan view thereof; and

FIG. 17 is a top front right side perspective view of the container of FIG. 1 in a closed position.
